UNITED STATES PATENT OFFICE.

HERBERT R. KEITHLEY, OF BUFFALO, NEW YORK.

DESIGN FOR A RAILWAY-CAR SILL.

SPECIFICATION forming part of Design No. 33,340, dated October 9, 1900.

Application filed September 6, 1900. Serial No. 29,237. Term of patent 14 years.

To all whom it may concern:

Be it known that I, HERBERT R. KEITHLEY, a citizen of the United States, residing at Buffalo, in the county of Erie and State of New York, have invented and produced a new and original Design for a Railway-Car Sill, of which the following is a specification, reference being had to the accompanying drawings, forming part thereof.

1c This design relates to the shape or configuration of a sill for railway-cars.

In the accompanying drawings, Figures 1 and 2 are perspective views of a car-sill embodying my design, showing the sill from opposite sides.

15 As shown in the drawings, the leading feature of my design consists of a vertical web having a comparatively-deep middle portion a , shallow end portion a' , and intermediate portions a^2 , which gradually increase in depth from said contracted end portions toward said deep middle portion, an upper horizontal flange B, projecting from the upper edge of

said web and extending throughout the length thereof, and a lower flange projecting from the lower edge of said web and facing in the opposite direction from said upper flange and comprising a horizontal middle portion c , which extends along the deep middle portion a of said web, horizontal end portions c' , which extend along the contracted end portions a' of the web, and oppositely-inclined intermediate portions c^2 , which extend along the intermediate portions a^2 of the web and slope from the end portions c' to the horizontal middle portion c^2 of said lower flange.

25 What I claim is—

The design for a railway-car sill, substantially as herein shown and described.

30 Witness my hand this 31st day of August, 1900.

HERBERT R. KEITHLEY.
